UNITED STATES PATENT OFFICE.

GEORGE WILKINSON, OF PROVIDENCE, RHODE ISLAND, ASSIGNOR TO GORHAM MANUFACTURING COMPANY, OF SAME PLACE.

DESIGN FOR A SPOON OR FORK-HANDLE.

Specification forming part of Design No. 5,093, dated July 4, 1871.

To all whom it may concern:

Be it known that I, GEORGE WILKINSON, of the city and county of Providence and State of Rhode Island, have originated a new design in articles of silver and plated ware for spoons and forks, of which the accompanying photographs, with this specification, are a full and complete description—that is to say, the article of spoons and forks, substantially as shown in the said photographs.

I claim—

The design for spoons and forks, substantially as herein set forth.

Witnesses: GEORGE WILKINSON,
CHARLES H. BAKER,
JOHN F. P. LAWTON.
